UNITED STATES PATENT OFFICE.

HOMER P. SMITH, OF APPLETON, WISCONSIN, ASSIGNOR TO MARGARET SMITH, OF
APPLETON, WISCONSIN.

HAIRPIN-CRIMPING MACHINERY.

Application filed February 20, 1922. Serial No. 537,780.

To all whom it may concern:

Be it known that I, HOMER P. SMITH, a citizen of the United States, residing at Appleton, in the county of Outagamie and State of Wisconsin, have invented new and useful Improvements in Hairpin-Crimping Machinery, of which the following is a full, clear, concise, and exact description, reference being had to the accompanying drawings forming a part of this specification.

This invention relates to improvements in hairpin crimping machinery and the process of making an improved hairpin, and more particularly to an improved hairpin crimping machine whereby the crimps on the respective prongs of the hairpin can be angularly displaced with respect to each other at any angle desired.

It has been universally recognized by those skilled in the art that hairpins fitted with crimps on the respective prongs of the hairpin, which crimps are angularly disposed with respect to each other, would be much more satisfactory than hairpins in which the crimps on both prongs are positioned in the same plane. The difficulty in making the improved hairpin with the angularly disposed crimps resides in the construction of suitable machinery which would efficiently and effectively produce hairpins of the improved type.

It is one of the objects of this invention, therefore, to provide an improved machine of this character whereby the crimps on the two prongs of the hairpin can be readily and efficiently placed on said prongs at any angular relation to each other.

Another object of the invention resides in an improved means for gripping the wire during the crimping operation.

A further object of the invention resides in the production of an improved means for angularly displacing the wire gripping means between the successive crimping operations on the two prongs of the hairpin.

An additional object consists in the production of improved means for adjusting the amount of angular displacement to be obtained between the crimps on the prongs of the hairpin.

Other objects of the invention will be ap-

parent from the following description; the accompanying drawings, and the appended claims. To simplify the description, a preferred form of the invention is illustrated 55 in the accompanying drawings, in which:

Figure 1 is a front elevation of the improved machine;

Fig. 2 is a cross-section taken on the plane represented by the line 2—2 in Figure 4 60 of the wire-gripping and wire-rotating means, the apparatus in the figure being illustrated in its normal position;

Fig. 3 is an illustration similar to Figure 2 with the wire-rotating means moved to its 65 most advanced position;

Fig. 4 is a longitudinal section taken on the plane represented by the line 4—4 in Figure 2 and illustrates the wire-gripping means and the wire-crimping dies; 70

Fig. 5 is an enlarged vertical cross-sectional view of the wire-gripping means taken on the plane represented by the line 5—5 of Figure 3;

Fig. 6 is an illustration of the wire-crimping die taken on the plane represented by line 6—6 of Figure 4; 75

Fig. 7 is an enlarged view in perspective of the wire-gripping clutch; and,

Fig. 8 is an illustration of a hairpin in 80 which the crimps on the respective prongs are angularly disposed at 90° degrees.

As illustrated in the drawings, the wire-gripping, advancing and crimping means are preferably mounted on a suitable table 85 or standard 10 equipped with suitable legs such as 11 and a machine-bed 12. Mounted upon the bed 12, as illustrated in Figure 1, is the wire-gripping mechanism 13 and the mechanism of the two wire-crimping dies 90 14 and 15. Figure 1 also shows a diagrammatical form of wire-advancing means 16.

As illustrated in Figure 1, the wire 17 from which the hairpins are made is threaded through the wire-gripping means 13 and 95 the crimping dies 18 and 19, the wire-advancing means 16 being operated by means well known in the art to advance the wire 17 the length of the hairpin immediately after the crimps have been impressed upon 100 the two prongs of the hairpin. The wire-gripping means 20 is operated by a cam 21

positioned on a rotating disc 22. The disc 22 is mounted on a suitable shaft 23, which shaft is rotatably mounted in any suitable bearings such as 24. Mounted on the same shaft 23 are the cams 28 and 29 which serve to operate the crimping dies 18 and 19.

As clearly illustrated in Figures 4, 5 and 7, the wire-gripping means comprises a tapered clutch mechanism. This tapered clutch mechanism, as clearly illustrated in Figure 7, consists primarily of two cooperating conical sections 30 and 31, which are fitted at their center with a rectangular groove 32 which serves to grip the wire 17. The conical sections 30 and 31 are fitted in a tapered housing 33 in such a manner that when the conical sections 30 and 31 are advanced forwardly in said housing, they will be drawn together, and the wire 17 will be clamped in the rectangular gripping groove 32. Obviously, the groove in said rectangular sections may take any desired form, but the rectangular groove has given very satisfactory results. The conical housing 33 has an extension 34 which is fitted with a cylindrical aperture 35 in which is mounted the helical spring 36. The helical spring 36 is retained in the cylindrical aperture 35 at one end by the adjusting nut 38, and at the other end by the wire-clutch or gripping means comprising the two conical sections 30 and 31.

The two conical gripping sections 30 and 31 are held in position in the tapered housing 33 by means of a lever arm 40, which lever arm is pivoted at 41. As clearly illustrated in Figures 4 and 5, this lever arm 40 is pivotally mounted upon an upright 42 secured to the base-plate 12 of the machine table. The lever 40 is fitted at its upper end with the roller 43 and at its lower end with a protruding knob 44 which rides against the ends of the conical gripping sections 30 and 31. The knob 44 is fitted with an aperture 45, through which the wire 17 is threaded. The roller 43, mounted on the upper end of the lever arm 40, rides upon the side face of the disc 22 and the cam surface 21 secured to the rotatable disc 22. The spring 36, clearly illustrated in Figure 5, is always in compression, and tends to force the conical wire-gripping sections 30 and 31 out of the housing 33. The movement of the sections 30 and 31 out of the housing 33 under the influence of the spring 36 is controlled by the knob 44 on the lever arm 40, the amount of said movement being equal to the rise of the cam surface 21 above the plane side surface of the rotating disc 22. The amount of compression of the spring 36 can also be adjusted by the nut 38, as will clearly be evident from an inspection of Figure 5. The nut 38 is equipped with a central aperture 50 through which the wire 17 is also threaded. As clearly indicated in Figure

5, the wire 17 passes through the aperture 45 fitted in the knob 44, then through the gripping aperture 32 of the conical gripping sections 30 and 31, thence through substantially the center portion of the helical spring 36, and finally through the aperture 50 of the adjusting nut 38 from where the wire 17 passes into and through the crimping dies 18 and 19.

From an inspection of Figure 5, it will now be evident that when the roller 43 of the lever arm 40 rides over the high point of the cam surface 21, the conical sections 30 and 31 will be advanced onto the housing 33, and, due to the tapered construction of the inside of said housing, which tapered surface is fitted with substantially the same slope as the external tapered surface of the sections 30 and 31, these sections will be compressed to grip the wires 17 in the gripping aperture 32. The rotation of the disc 22 with its cooperating cam 21 is so timed in the machine that immediately after the wire has been advanced preparatory to a crimping operation, this gripping means will be actuated so as to firmly grip the wire between the conical sections 30 and 31.

In the operation of the machine, after the wire has been firmly gripped, one of the dies, 18 or 19, is operated to crimp the wire. Following this crimping operation the wire is rotated through a desired angle before the second crimping operation is performed. This angular displacement of the wire is performed by the mechanism illustrated in Figures 2 and 3, the angular displacement of the wire being regulated and adjusted by the mechanism there shown.

As clearly illustrated in these figures, the housing 33 is enclosed and has secured to it the gear wheel 56. This gear wheel 56 meshes and cooperates with a rack 57 secured to the lower edge of a reciprocating bar 58. The bar 58 has attached to one end thereof a shoulder 59, which shoulder is fitted with perforations 60 and 61. Passing through the perforation 60 is a cylindrical rod 62, the forward end 63 of which is rectangular in shape. The rectangular portion 63 of the said rod, as shown in Figure 5, is equipped with a key 64 which rides in a key-way 65 fitted in the upper portion of the reciprocating bar 58. Due to the cooperating action of the key-way 65 and the key 64, the rod 63 may be slid upon the surface 120 of the bar 58. The cylindrical portion 62 of the rod passes through the aperture 60 in the shoulder 59 of the rod 58 and extends through said aperture for a sufficient length to receive the spiral spring 66, which spring 125 is held on said rod against the shoulder 59 by means of the jam nuts 67 threaded on the end of the rod 60. The rod 60, together with the integral rectangular portion 63 and the bar 58 are held in position by the housing 70. 130

The bar 58 is also preferably fitted with a cylindrical portion 71 on which is mounted the spiral spring 72. The spiral spring 72 is held on the cylindrical portion 71 of the 5 rod 58 by means of the shoulder 73 and the mounting bracket 74, secured to the bed-plate of the machine table by means of screws such as 75. The mounting bracket 74 is perforated to permit the passage therethrough of 10 the end of the cylindrical rod 71, on which are secured the jam nuts 75, as clearly illustrated in Figures 2 and 3.

Mounted in the perforation 61 of the shoulder 59 is the adjusting bolt 78, which 15 bolt determines the length of travel of the bar 58 when the said bar is advanced to rotate the gear 56 to angularly displace the wire 17 positioned in the machine. The bolt 78 is held in its adjusted position by the jam 20 nut 79, and the amount of angular displacement of the wire 17 is controlled by the positioning of the adjusting bolt 78.

Mounted on the rotating disc 22 is a projecting finger 80, which finger 80 is the means 25 used for advancing the mechanism just described to rotate the wire through the desired angular displacement.

Figure 2 shows the wire rotating means in its normal position. As the disc 22 is 30 rotated clockwise, the finger 80 strikes a protrusion 82 on the rectangular portion 63 of the rod 60. When the finger 80 hits the protrusion 82, the bar 58, together with the rod 60, is advanced and the bar 58, as it is 35 advanced, rotates the gear 56 because of the cooperating inner action of the rack 57 and the said gear 56. The bar 48 will continue to advance until the end of the adjustment bolt strikes the face of the housing 70. When the apparatus reaches this 40 point in its operation, the bar 58 will cease to move and from this time on the rod 60, together with its rectangular portion 63, will slide on the upper face of the bar 58 in the key and key-way hereinbefore described. The bar 58 and the rod 60 move together in the initial movement of this apparatus because the spiral spring 66 is considerably heavier and offers greater resistive power 45 than the spiral spring 71. However, when the end of the adjustment bolt 78 hits the face of the housing 70, the bar 58 can move no further, and at this point the rod 62 will be advanced individually by the finger 80 50 which will continue to move the rod 62 against the compressive force of the spiral spring 66. This movement of the rod 62 against the resistive power of the spring 66 will continue until the finger 80 clears the 55 protrusion 82, which condition of the apparatus is illustrated in Figure 4.

It will be evident from the foregoing description that as the bar 58 is advanced and the rack 57 rotates the gear wheel 56, the

wire 17 held in the conical gripping sections 65 30 and 31 will be rotated through an angular displacement depending upon the amount of movement attained by the bar 58. As hereinbefore described the amount of this movement is controlled and regulated by the 70 adjustment bolt 78. After the finger 80 slides over and by the protrusion 82 on the rectangular section 63 of the rod 62, the spring 66, which at this moment is under severe compression, will expand and thereby 75 will return the rod 62 and the bar 58 to their normal position, as indicated in Figure 2.

The dies utilized for crimping the wire may be of any type well known in the art, 80 but are preferably of the quick acting type whereby the crimp in the wire can be rapidly made at the proper moment when the wire has been properly adjusted in position by the wire-advancing and gripping mechanism. A preferred form of this die is illustrated in Figures 4 and 6. The dies are operated by cams such as 28 and 29, which cams cooperate with rollers such as 90 and 91 positioned on the upper part of the movable portion of the die. The lower part of the dies 92 and 93 are secured to the base plate 10 and the lower die proper 94 is adjusted in its proper position by any suitable means such as, for example, the adjustment 95 nut 95, as clearly shown in Figs. 4 and 6. The die is held in its open position by means of spiral springs such as 96 and 97. In the operation of the die, when the high part of the cam rides over either the roller 90 100 or 91, the upper die proper 98 is depressed against the resistive force of the springs 96 and 97 and the wire is crimped between the operating faces of the lower die proper 94 and the upper die proper 98. Obviously, 105 any form of die construction could readily be used in place of the specific form herein illustrated and described.

In the operation of the machine, the wire is threaded through the wire-gripping and 110 rotating means, as illustrated in Figures 1, 4 and 5, and is then threaded through the two crimping dies. After the wire has been threaded through the apparatus in this manner, as shown in Figure 4, the machine may 115 be started, which consists in driving the shaft 23 in any suitable manner. The rotation of the shaft 23 will rotate with it the disc 22 and the two cams 28 and 29 secured thereto. The disc 22 and the cams 28 and 120 29 are so positioned on the shaft 23 that the various operations performed by the wire-gripping means; the wire-rotating means, and the wire-crimping means will be operated in proper sequence and at the proper 125 time. Thus, as the shaft 23 rotates, the first operation of the machine consists in rotating the lever 40 about its center 41 where-

by the tapered sections 30 and 31 of the wire-gripping means will firmly grip the wire 17 in position. While the wire is thus gripped in this position, one of the crimping dies 5 will be next actuated to impress the crimp on one of the prongs of the ultimate hairpin.

Immediately following this crimping operation, the wire rotating or angular displacing mechanism will be started. Thus, after the first crimping operation is performed, the finger 80 will strike the protrusion 82 on the rectangular portion 63 of the rod 62, and the wire-rotating means will 10 operate and function as hereinbefore described to rotate the wire 17 through the desired angular displacement. When the wire has been thus displaced and while the finger 80 is advancing the rod 62 against 15 the compressive action of the spring 66, during which period the rod 62 slides on the top surface of the bar 58, the second crimping die is operated, which impresses the crimp on the second prong of the hairpin. 20 Inasmuch as the wire 17 has been rotated through a desired angle, this second crimp on the wire will be angularly displaced from the crimp originally placed upon the wire, the angular displacement between the two 25 crimps depending upon the amount of movement given to the bar 58, which, in turn, determines the amount of rotation of the gear 56, the wire-gripping clutch and the wire 17.

Following the second crimping operation, the finger 80 slides over the protrusion 82 and the wire rotating means is returned to its normal position under the action of the spring 66, as hereinbefore described, and as 30 illustrated in Figure 2. At the same time, the lever arm 40 gradually rides off of the face of the cam surface 21 and the conical gripping sections 30 and 31 are pushed out of the housing 33 to release the wire 17. 35 The wire-advancing means 16 is then operated to advance the wire 17 the length of another hairpin. When the wire has been advanced, the operation just described will be repeated and another hairpin will be 40 crimped.

As illustrated in Figure 8, the hairpins which are made in this machine have the crimps on the respective prongs of said hairpin displaced at an angular position. The 45 illustration in Figure 8 shows the hairpin with these crimps 98 and 99 displaced 90 degrees with respect to each other. Obviously, with the mechanism hereinbefore described, these crimps can be disposed at any 50 desired angular displacement. The angular displacement of these crimps is controlled by the adjustment bolt 78, as hereinbefore described.

The improved process for making hairpins

with angularly disposed crimps on the respective prongs thereof, together with the machinery for making said hairpins, produces these improved hairpins in a very efficient, rapid and economical manner whereby the improved hairpin with the angularly displaced crimps can be made substantially as efficiently and as cheaply as the ordinary type of hairpin in which the crimps on the respective prongs are disposed in the same plane. The machine for making these improved types of hairpins is extremely simple in its construction and comprises but few simple parts which are easily retained in adjustment and consequently the machine and the process can be efficiently and economically operated.

Obviously, the invention is not limited to the specific embodiment thereof herein illustrated and described, but is capable of many variations and other applications within the spirit and scope of the invention as set forth in the following claims.

What I claim as new and desire to secure by Letters Patent of the United States is:

1. An improved process for making hairpins with angularly displaced crimps on the respective prongs of said hairpin which consists in gripping the wire for the crimping operation on both prongs of said hairpin, then crimping one prong of said hairpin, 95 then rotating the said wire through the desired angular displacement and thereafter crimping the second prong of said hairpin.

2. An improved process for making hairpins with angularly displaced crimps on the respective prongs of said hairpin which consists in gripping the wire for the crimping operation on both prongs of said hairpin, then crimping one prong of said hairpin, 100 then rotating the said wire through the desired angular displacement, thereafter crimping the second prong of said hairpin, and finally returning the wire to its original angular position, and then releasing the wire-gripping means.

3. An improved process for making hairpins with angularly disposed crimps on the respective prongs of said hairpin, which consists in gripping the wire for the crimping operation on both prongs of said hairpin and then rotating the wire through the 115 said desired angular displacement between the crimping operation on the two prongs of the hairpin.

4. An improved process for making hairpins with angularly disposed crimps on the respective prongs of said hairpin, which consists in gripping the wire for the crimping operation; then crimping one prong of said hairpin, then rotating the said wire- 120 gripping means through the desired angular displacement, and thereafter crimping the second prong of said hairpin.

5. In a machine of the character described, in combination, a wire-advancing means, a wire-gripping means, a plurality of wire-crimping dies, and means for rotating the wire-gripping means following the operation of each wire-crimping die. 65
6. In a machine of the character described, in combination, a wire-advancing means, a wire-gripping means, a plurality of wire-crimping dies, and a cooperating gear and rack for rotating the wire-gripping means following the operation of each wire-crimping die. 70
- 10 7. In a machine of the character described, in combination, a wire-advancing means, a wire-gripping means, a plurality of wire-crimping dies, means for rotating the wire-gripping means, and means for adjusting the angular displacement of said rotation. 75
- 20 8. In a machine of the character described, in combination, a wire-advancing means, a tapered clutch wire gripping means adapted to grip said wire, a wire-crimping means adapted to crimp the said wire after it is gripped by said clutch, and a means for rotating said wire in said gripping means after said crimping operation. 80
9. In a machine of the character described, in combination, a wire-advancing means, a tapered clutch, a housing for receiving said tapered clutch to grip said wire, a wire-crimping means adapted to crimp said wire after it is gripped by said clutch, and means for rotating said clutch with the wire in its gripped position after it has been crimped. 85
- 30 10. In a machine of the character described, in combination, a wire-advancing means, a tapered clutch wire-gripping means adapted to grip said wire, a tapered clutch housing adapted to receive said tapered clutch to grip said wire, a wire-crimping means adapted to crimp the said wire after it is gripped by said clutch, a gear surrounding and secured to said tapered clutch housing, a rack cooperating with said gear, means for moving the rack to rotate the said clutch-housing, clutch and gripped wire after said wire has been crimped, and a second wire crimping means adapted to crimp said wire after it has been rotated. 90
- 40 11. In a machine of the character described, in combination, a wire-advancing means, a tapered clutch wire-gripping means adapted to grip said wire, a tapered clutch housing adapted to receive said tapered clutch, means for advancing the tapered clutch in said housing whereby said clutch will grip said wire, a wire-crimping means adapted to crimp the said wire after it has been thus gripped, and a wire-rotating means adapted to rotate said wire after it has been crimped. 95
- 50 12. In a machine of the character described, in combination, a wire-advancing means, a wire-gripping means, a plurality of wire-crimping dies, means for rotating the wire-gripping means, and adjustable means adapted to automatically determine the amount of angular displacement of said wire-rotating means. 100
- 60 13. In a machine of the character described, in combination, a wire-advancing means, a wire-gripping means, a plurality of wire-crimping dies, means for rotating the wire-gripping means following each wire-crimping die operation, and adjustable means for determining the amount of rotation of the wire-gripping means. 105
- 70 14. In a machine of the character described, in combination, a wire-advancing means, a tapered clutch adapted to grip said wire, a tapered clutch housing adapted to receive said tapered clutch, means for operating said tapered clutch in the said housing to grip said wire, wire-crimping means adapted to crimp the said wire after it is gripped by said clutch, a gear surrounding and secured to said tapered clutch housing, a rack cooperating with said gear, means to move said rack to rotate said clutch housing, adjustable means adapted to determine the amount of said rack movement, and a second wire-crimping means adapted to crimp said wire after it has been rotated. 110
- 80 15. In a device of the character described, the combination with a wire-crimping means, of a wire-gripping means comprising two cooperating conical sections, a wire-gripping groove in said sections, a conical housing for said gripping sections, means for advancing said sections in said housing to grip said wire, and a gear and rack cooperating with said housing to rotate said wire when held in said gripping means. 115
- 90 16. In a device of the character described, the combination with a wire-crimping means, of a wire-gripping means comprising two cooperating conical sections, a wire-gripping groove in said sections, a conical housing for said gripping sections, means for advancing said sections in said housing to grip said wire, a gear and rack cooperating with said housing to rotate said wire when held in said gripping means, and means for adjusting the amount of said rotation. 120
- 100 17. In a device of the character described, the combination with a wire-crimping means, of a wire-gripping means comprising two conical cooperating sections, a wire-gripping groove in said sections, a conical housing for said gripping sections, means for advancing said sections in said housing to grip said wire, a gear and rack cooperating with said housing to rotate said wire when held in said gripping sections, a spring resisting the movement of said rack, and 125

means operated to automatically return said rack to its normal position after the crimping operation is completed.

18. In a device of the character described, the combination with a plurality of wire-crimping means, of a wire-rotating means comprising a cooperating gear and rack for

rotating said wire through a desired angular displacement between the successive operations of said plurality of crimping means. 10

In witness whereof, I have hereunto subscribed my name.

HOMER P. SMITH.
